(57) **CLAIM**

The ornamental design for a dispenser for cartridges, as shown and described.

DESCRIPTION

FIG. 1 is a top, front, and right side perspective view of a dispenser for cartridges showing my new design;

FIG. 2 is a top, rear, and right side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line showing portions of the dispenser, cartridge support structure, and exemplary cartridges in the drawings do not form part of the claimed design.

1 Claim, 7 Drawing Sheets(56)
